(57) **CLAIM**

The ornamental design for a data projector, as shown and described.

DESCRIPTION

FIG. 1 is a front elevational view showing my new design for data projector;

FIG. 2 is a top plan view thereof;

FIG. 3 is a right side elevational view thereof;

FIG. 4 is a left side elevational view thereof;

FIG. 5 is a bottom plan view thereof;

FIG. 6 is a rear elevational view thereof;

FIG. 7 is a cross-sectional view thereof taken along the line 1—1, wherein the inner workings are omitted;

FIG. 8 is a cross-sectional view thereof taken along the line 2—2, wherein the inner workings are omitted;

FIG. 9 is a cross-sectional view thereof taken along the line 3—3, wherein the inner workings are omitted;

FIG. 10 is a perspective view thereof, as viewed from the front right;

FIG. 11 is a perspective view thereof, as viewed from the rear left;

FIG. 12 is a front elevational view thereof in the state of the shutter being closed;

FIG. 13 is a top plan view thereof in the state of the shutter being closed;

FIG. 14 is a bottom plan view thereof in the state of the shutter being closed; and,

FIG. 15 is a rear elevational view thereof in the state of the shutter being closed.
